Primary Examiner — Kevin K Rudzinski*Assistant Examiner* — Kathleen L Jones(74) Attorney, Agent, or Firm — Brett M. Maland(57) CLAIM

The ornamental design for a front sight post, as shown and described.

DESCRIPTION

FIG. 1 is a top front perspective view of the new design; FIG. 2 is a side view thereof; and, FIG. 3 is a top view thereof.

The new design appears the same as in FIG. 2 on three other side views.

The broken lines in the Figures show portions of the new design that form no part of the claimed design.

The shade lines in the Figures show contour and not surface ornamentation.
